(57) CLAIM

The ornamental design for a portion of a slipper, as shown.

DESCRIPTION

FIG. 1 is a perspective view of the top, right side and front of a slipper portion, wherein no claim is made to the sole; FIG. 2 is a top plan view of the slipper portion; FIG. 3 is a bottom plan view of the slipper portion; FIG. 4 is a front elevation view of the slipper portion; FIG. 5 is a rear elevation view of the slipper portion; FIG. 6 is a right side elevation view of the slipper portion; and,

FIG. 7 is a left side elevation view of the slipper portion. It should be understood that in all embodiments, no claim to color is made. It should also be understood that the tread pattern on the bottom of the outsole is not claimed as an ornamental feature of our design. It should further be understood that alternative seam appearances are contemplated. For example, different stitching patterns may be used. Glued rather than stitched seams may be substituted in the claimed invention. Alternatives are also contemplated for the sole thickness, fabric texture, midsole thickness, area of the wearer's foot that is covered by the upper, and other features. The overall size of the slipper may range within the range of different shoe sizes typically made commercially available. Additionally, no claim is made to the indicia "zizi".
